COMBINED COSMETIC AND FLASHLIGHT HOLDER

Norman Burkhardt, Glenhead, N.Y., assignor to Jarco
Metal Products Corp., Westbury, N.Y., a corporation of New York

Filed Oct. 3, 1966, Ser. No. 4,150

Term of patent 14 years

(Cl. D86—10)

FIG. 1

FIG. 2

FIG. 3

FIG. 4

FIG. 6

FIG. 5

I claim:

The ornamental design for a combined cosmetic and flashlight holder, as shown.
